UNITED STATES PATENT OFFICE.

JACQUES BOTELLA, OF PARIS, FRANCE.

MOTOR-CAR BODY AND COLLAPSIBLE TOP THEREFOR.

Application filed March 8, 1922. Serial No. 542,093.

To all whom it may concern:

Be it known that I, JACQUES BOTELLA, a citizen of the French Republic, residing at 3 Rue Georges Ville, Paris, France, have invented new and useful Improvements in a Motor-Car Body and Collapsible Top Therefor, of which the following is the specification.

In the carriage bodies of motor cars of the torpedo type a housing is actually provided at the rear and on the sides of the rear seats, this housing being closed by a leather apron or a rigid cover and being adapted to enclose the top when it is not in use. In these devices, the upper cover of the housing is removable so that it can be opened for allowing the passage of the hoops of the top; consequently there is a vertical joint which is not water tight. Besides, these devices have the inconvenience of permitting the jarring of the covers for the housing of the top, thus causing noise and in addition being difficult to operate.

The present invention relates to a method of collapsing and housing the tops of motor cars, characterized in that the housing of the hood is closed at its upper part and on three lateral sides by fixed partitions, the top being extensible upon the opening of a side movable partition provided with integral ledges forming butt-plates; the displacement of this movable partition which can be constituted by the rear seat permits of the removing of the top from the housing in order to effect an extension thereof.

By means of this method, the following results are obtained:

(1) a perfect water-tightness of the housing of the top, which no longer presents joints with vertical faces,

(2) a very great ease of operation,

(3) the suppression of noise caused by jarring.

A practical form of execution in which the side movable partition is constituted by the rear seat itself, is illustrated by way of example in the accompanying drawing wherein:

Fig. 1 is a partial elevation showing the rear of a carriage body of the "bridge" type, with the position occupied by the top in its housing and in use.

Fig. 2 is an elevation similar to the previous one, showing the operation of unfolding the top.

Fig. 3 is a corresponding plan view show-

ing the shape of the seat and the top collapsed and arranged in its housing.

Fig. 4 is a similar view showing the seat, which is pivoted for leaving enough space for the unfolding of the hood.

In this form of execution, the top *c*, when it is not in use, is located in a space *i* limited laterally by the partition of the carriage body and at its upper part by a roof *k* integral with the carriage body and forming the rear of the bridge, which is inclined outwardly for permitting water to flow away.

The rear seat *m* closes the housing or chest on the inside of the car. The top *c* is hinged at *b*, on an axis integral with the elbow rests of the seat *m*. For permitting its opening the latter is made movable, so as to leave a sufficient space between the carriage body and the said seat, through which the top will be unfolded.

The back of the seat and the elbow rests, when the top is in its housing, form butt-plates. Besides, the width of the back of the seat is smaller than the width of the seat between the elbow rests, as shown in Figures 3 and 4, so that by moving the seat *m* away from the housing or chest, a free space is left in which the top may be unfolded. Once this top is unfolded, the seat *m* is put back into place so that the lining *l* extending beyond the seat fits on the joints and renders the housing or chest completely water-tight.

The displacement of the seat *m* may take place longitudinally (Fig. 1) the seat being then mounted on rollers or slides parallel to the sides of the car, or by rotation about an axis *a* (Fig. 2.) In the latter case, the seat *m* is jointed by means of a hinge *a* secured to the cushion frame; consequently, the end of the back of the seat and the hoops of the top describe an arc of a circle and the top has so much the more room for being unfolded as the pivoting of the seat is more accentuated.

The operation of the device is as follows:

Supposing the top is in its housing, the seat *m* is pulled forward, or is subjected to a rotation about the axis *a*, until the hoops of the top are removed from the housing. At this moment, these hoops are subjected to such a rotation that they are completely placed in their normal position relatively to the seat, which is brought back to its initial position.

In case the seat moves on slides, it is first

pulled forward to the required extent for permitting the rotation of the hoops of the top, their disengagement and their putting in position relatively to the seat; subsequently the seat is pushed back until it resumes its initial position.

It is to be noted that the device described can be applied in a similar manner to all other systems of carriage bodies.

10 What I claim as my invention and desire to secure by Letters Patent is:

1. In an automobile body, in combination, a movable seat, a collapsible top including bows pivoted to the lateral surfaces of 15 the seat, a housing provided between the rear portion of the body and the seat for the lodgment of the top when collapsed, the seat being adapted to occupy two positions, one in which it permits the passage of the

top between the seat and the body so that 20 the top may be received in the housing and the other, its position of use, in which it conceals the collapsed top.

2. In combination, an automobile body, a housing provided in the rear of the body, a 20 seat in the body serving as a closure for the housing, a collapsible top including bows pivoted to the lateral surfaces of the seat, and means for mounting the seat so that it may be moved relatively to the bottom of 25 the body so as to uncover the housing and permit of the collapsing of the top and the arrangement of the top within the housing, and the seat being returnable to its initial position for concealing the top. 30

In testimony whereof I have signed my name to this specification.

JACQUES BOTELLA.
